UNITED STATES PATENT OFFICE.

FRANK PASTOR, OF AKRON, OHIO.

LANTERN-SUPPORT.

1,120,740.

Specification of Letters Patent. Patented Dec. 15, 1914.

Application filed August 5, 1914. Serial No. 855,173.

To all whom it may concern:

Be it known that I, FRANK PASTOR, a subject of the Emperor of Austria-Hungary, residing at Akron, in the county of Summit 5 and State of Ohio, have invented certain new and useful Improvements in Lantern-Supports, of which the following is a specification.

This invention relates to certain new and 10 useful improvements in lantern supports.

An object of the invention is to provide a support for hand lanterns in the form of braces or arms that are adapted to engage the support on which the lamp is resting to 15 prevent the lamp from being upset or being otherwise injured.

A further object of the invention is to provide a lantern support in the form of a wire cage that surrounds the lantern globe to protect 20 the same from injury, and adapted to be brought into engagement with the support on which the lantern is resting to prevent the same from being thrown over.

With the above general objects in view 25 and others that will appear as the nature of the invention is better understood, the same consists in the novel construction, combination and arrangement of parts to be herein-after more fully described and then claimed.

30 In the accompanying drawing forming a part of this application, and to which reference is had herein by like characters designating corresponding parts throughout the several views, Figure 1 is a side elevational 35 view of a lantern provided with the support in operative position. Fig. 2 is a side elevational view of the same in inoperative position or retracted, and Fig. 3 is a top plan view on a reduced scale of the lantern support, partly broken away.

Briefly described, the invention consists 40 of a wire cage or support carrying a lantern base or reservoir receptacle that may be used in connection with the lantern of the ordinary type, and in which the oil reservoir of the lantern is received in a cushioned receptacle with the said wire cage or support surrounding the lantern globe to protect the same from injury. The bail handle is secured 45 to the upper end of the cage, and causes the supporting feet for the lantern to be retracted to the position shown in Fig. 2 when the lantern is removed from a support, while springs arranged in the recep-

tacle engage the bottom of the lantern reservoir, and are compressed as shown in Fig. 1 by weight of the lantern, and when the bail handle is released.

Referring more in detail to the accompanying drawing, I have shown a lantern 60 of conventional form comprising the oil reservoir A, burner B, and globe C.

A cage or support for the lantern consists of a receptacle 10 having hinged to the bottom thereof as at 11, a bottom closure 12 65 provided with a resilient snap fastening 13 of suitable construction by which the same is held to the receptacle 10 in locked position. The oil reservoir A is received in the receptacle 10 and is seated on compression 70 coil springs 14, the purpose of which will presently appear.

Pivottally connected to the upper edge of the receptacle 10 preferably at equi-distantly spaced points, are a plurality of links 15 75 pivottally connected at their outer ends as at 16 to the supporting feet or legs 17, the said legs being bent at their upper ends as at 18 to be received on the ring 19. The legs 17 are of suitable length so that the ring 19 80 will be spaced thereabove a desired distance, while a lifting bail or handle 20 for the lantern is secured as at 21 to the ring 19.

In the position shown in Fig. 2, the lantern is sustained by the bail 20 and the 85 springs 14 will be distended to separate the receptacle 10 and lantern reservoir A, and thereby bring to retracted position the arms 17, which will be moved to such position by the connecting links 15. The lantern A is 90 limited in its movement relative to the receptacle 10 by the globe C contacting the upper ring 19. As shown in Fig. 1 the lantern is resting on a suitable support with the legs 17 distended, and caused to engage the 95 said support to prevent the lantern from being upset. In such position, the bail 20 is utilized to move in a slight downward direction, the ring 19 which has connected thereto the supporting arms 17, and by 100 reason of the link connection 15 with the receptacle 10, the said arms will be moved downwardly as shown in the said figure.

While I have shown and described the preferred embodiments of the present invention, I do not wish to confine myself to the exact details of construction shown, and various forms, modifications and arrange-

ment of the parts as shown may be had without departing from the spirit and scope of the invention as claimed.

What I claim as new is:—

- 5 1. In a lantern support, a receptacle, a hinged bottom, cushion springs received in said receptacle, links pivoted at one end to the upper edge of the receptacle, arms pivoted intermediate their ends to the other 10 ends of said links, a ring connecting the upper ends of said arms and a bail connected to said ring, said arms adapted to be moved outwardly to engage the support on which the lantern is mounted to prevent the same 15 from tilting.
2. In a lantern support, a receptacle, links pivoted to said receptacle, arms pivoted intermediate their ends to said links, a ring connecting the upper end of said arms and a 20 bail connected to said ring, said arms adapt-

ed to be moved outwardly to engage the support on which the lantern is mounted to prevent the same from tilting.

3. The combination with a lantern, of a receptacle having a hinged bottom, cushion 25 springs in said receptacle adapted to engage the lantern reservoir, links pivoted to said receptacle, supporting arms pivoted to said links, and a retaining ring for the upper ends of said arms, said arms adapted to 30 be moved outwardly to engage the support on which the lantern is mounted to prevent the same from tilting.

In testimony whereof I affix my signature in presence of two witnesses.

FRANK PASTOR.
